UNITED STATES PATENT OFFICE.

OSGOOD PLUMMER, OF WORCESTER, AND CHARLES E. MONROE, OF BOSTON, MASSACHUSETTS, ASSIGNORS TO FRANK O. PLUMMER, OF BOSTON, MASSACHUSETTS.

TELEPHONE-SWITCH.

SPECIFICATION forming part of Letters Patent No. 652,922, dated July 3, 1900.

Application filed January 4, 1900. Serial No. 308. (No model.)

To all whom it may concern:

Be it known that we, OSGOOD PLUMMER, residing at Worcester, in the county of Worcester, and CHARLES E. MONROE, residing at 5 Boston, in the county of Suffolk, State of Massachusetts, citizens of the United States, have invented a new and useful Telephone-Switch, of which the following is a specification.

10 Our invention relates to that class of telephone-switchboards which are ordinarily employed in private telephone systems where there are a comparatively-small number of stations, one switchboard being employed in 15 connection with each telephone instrument; and the object of our present invention is to provide a simple, inexpensive, and efficient construction which will permit a simultaneous connection with several stations and in 20 which the parts are arranged so that they are not liable to accidental injury or derangement.

To these ends our invention consists of the parts and combinations of parts as hereinafter described, and more particularly pointed out in the claims at the end of this specification.

In the accompanying two sheets of drawings, Figure 1 is a transverse sectional view 30 of a switchboard constructed according to this invention. Fig. 2 is a partial perspective view showing the rear side of the face-plate to illustrate the manner in which a plurality of detent-strips may be connected together.

35 Fig. 3 is a detail view of a releasing or clearing-out button. Fig. 4 is a diagrammatic view illustrating the connections from a switchboard constructed according to this invention. Fig. 5 is a partial perspective view 40 illustrating a modified form of detent-strip. Fig. 6 is a transverse sectional view of the same, and Fig. 7 is a detail view of a call-button.

In a telephone-switchboard constructed according to the present invention a plurality 45 of circuit-making push-buttons or plungers are employed which extend through the front plate of the switchboard and may be arranged in tiers or banks, so that any desired number 50 of push-buttons may be embodied in each

switchboard. The plungers or push-buttons are normally pushed outwardly by springs, a separate spring being employed for each plunger. Coöperating with each plunger are terminals or contact-fingers, preferably two 55 such sets of contact-fingers coöperating with each plunger. The operating-piece on the plunger which controls the terminals or contact-fingers is preferably square or rectangular in cross-section to present a considerable 60 wearing-surface and to hold the plungers from turning or twisting. The operating-pieces are formed of hard rubber or other insulating material. The plungers are each provided with a catch or conical section, which is 65 engaged by a detent-strip to hold the same in its operative position after being pressed in. A plurality of detent-strips are employed where more than one tier or row of push-buttons is used, and we prefer to employ swing- 70 or pivotally-mounted detent-strips, as we have found in practice that a swinging or pivotally-mounted detent-strip is far less liable to cramp or bind than a detent-strip which is mounted to reciprocate or slide. Each plunger is also preferably provided with a conical 75 releasing or clearing-out section, which will raise the detent-strip far enough to release all previously-actuated plungers or push-buttons when a connection is desired with a single or individual subscriber.

Referring to the drawings and in detail, the telephone-switchboard herein illustrated comprises a face-plate 10, preferably of metal. Extending from the rear of the face-plate 10 85 are posts 11, carrying cross-strips or bridges 12. Extending through the face-plate 10 and preferably arranged in tiers over each other are the push-buttons or plungers 13. Each of the push-buttons or plungers is normally 90 forced outwardly by a coiled spring 14. The springs 14 are inclosed in sockets in the bridge-pieces 12. The sockets for receiving the springs 14 do not extend completely 95 through the bridge-pieces, and as the bridge-pieces are preferably made of hard rubber or other insulating material the springs 14 and the ends of the plungers will be inclosed, so that they will be protected from dirt or foreign matter which might get into the path 100

of motion of the plungers—as, for example, pieces of solder from dropping into the path of the plungers while connecting wires to the terminals. Near their inner ends the plungers or push-buttons 13 are provided with operating-sections 15, preferably rectangular or square in cross-section. The operating-section 15 of each plunger or push-button engages two terminals or contact-fingers 16 and is arranged to force the same apart to bring the contact-fingers 16 into engagement with fingers extending in from side strips or insulated combs 17.

We prefer to employ operating-sections 15 on the plungers which are rectangular in cross-section not only for the reason that said operating-pieces will have wearing-surfaces of considerable width, but also for the reason that the operating-pieces will prevent the plungers from being turned or rotated, so that when the parts of the switch have been once adjusted or set to exactly the proper relation the relative position of the parts will be maintained even when plungers which have been more or less sprung or are not exactly true are employed.

To hold a plunger in an operative or pushed-in position, as illustrated, for example, by the middle plunger shown in Fig. 1, each plunger is provided with a catch 18 for engaging behind detent-strips 19. The detent-strips 19 are mounted to swing or turn on pivots, as we have found in practice that this arrangement is more durable and can be operated with less friction than other forms with which we are familiar. Each of the plungers 13 is also provided with a clearing-out or releasing section 20 for lifting the detent-strip, and releasing any of the plungers which have been previously pushed in or operated.

When the push-buttons or plungers of a switchboard constructed according to this invention are arranged in tiers one over the other, the detent-strips 19 are preferably pivotally connected together—for example, by a rod or wire 21, as illustrated in Fig. 2—so that the detent-strips may be simultaneously turned or operated to release all push-buttons or plungers which may have been previously operated in the entire switchboard.

In addition to the circuit-making push-buttons or plungers we preferably employ in a switchboard constructed according to this invention a releasing or clearing-out plunger 22, (illustrated in Fig. 3,) which is of the same construction as circuit-making push-buttons or plungers, having a clearing-out or releasing section 23, but not being provided with the operating-piece or catch-section employed on the circuit-making buttons. The electrical connections from a switchboard as thus constructed are illustrated in Fig. 4. As shown in this figure, wires from the terminals 16 form the main line or cable L, wires from each set of terminals being carried to a telephone of the telephone system.

In the diagram shown in Fig. 4, B designates the local battery of a telephone; T, the transmitter thereof; C, the call-bell; I, the induction-coil; R, the receiver, and II the telephone-receiver hook, which also acts as a switch in the usual manner.

To generate a calling-current, we may employ an ordinary magneto or may take a current from a dynamo or other source, as indicated at D. The dynamo D is connected to terminals which may be controlled by a push-button of the same construction as the circuit-making push-button, except that the same is preferably constructed so as not to be held in or engage a detent-strip, as shown in Fig. 7. The first set of terminals (illustrated at the left of Fig. 4) are the local terminals *t* of the telephone instrument at the station illustrated.

When it is desired to make a call from a telephone-switchboard as thus connected, the desired push-button is pressed in, and by operating the push-button controlling the circuit from the dynamo the calling-current can be sent over the desired line.

When the calling-current is generated by a magneto instead of a dynamo, a call may be made by pressing in the push-button of the desired telephone and then turning the magneto by hand in the usual manner. When a magneto is employed, the use of the calling-button shown in Fig. 7 may be dispensed with.

When a call is received, the person receiving the call pushes in the plunger or push-button of his own instrument, and by then taking his telephone-receiver from the hook the ordinary connections will be made between the two telephone instruments. When the conversation is completed, the operator may clear his switchboard by operating the clearing-button, (illustrated in Fig. 3,) or if he desires to make any other call he may clear the board by pushing in the plunger or push-button of the station then desired to be called to the limit of its movement, so as to release the previously-operated push-button. In this manner any two instruments in the entire system may be put in circuit with each other as a pair or any number of instruments may be used in pairs at one and the same time to the limits of all the instruments in the system.

Each pair of instruments in circuit with each other will not disturb the other users, and the conversation between any pair of instruments will not be overheard or interfered with from any of the other instruments—that is to say, in its ordinary operation a telephone system provided with switchboards constructed according to our invention will constitute what may be considered a "non-interfering" system, by which we mean to signify a telephone system arranged so that any two telephones may be thrown into connection, and the connection between two such telephones will not ordinarily be interfered

with nor the conversation interrupted by other parties then using other instruments. In some cases, however, especially when telephone-switchboards constructed according to our invention are employed in warehouses, factories, or in different parts of the same large plant, it may be desirable for a person—for example, a manager of a large plant—in issuing orders to two or more departments to be able to hold a conversation with two or more people at the same time. Switchboards constructed according to our invention have been especially designed with a view of permitting this to be done, when desired. For example, if two parties are holding a conversation and it is desired to call in a third party, thereby changing the non-interfering into an interfering system, in which more than two persons may hear all that is passing over the line, the person desiring to call the third party will push in the desired push-button, and as this may be done without releasing or holding in the previously-operated push-buttons a person may talk with two or more persons at the same time, and more than two persons may thus be put into communication.

If the operator after having called up the third party or a person in addition to the one he was originally talking to desires to resume a non-interfering conversation with the one first called up by him, he may cut out the third party by simply pressing in the push-button originally called by him to the limit of its motion, thereby releasing previously-operated push-buttons and permitting him to continue a non-interfering or direct conversation with a single other person—that is to say, in a telephone-switchboard constructed according to our invention if the plungers are pushed to their limits of motion the system will be a non-interfering system, in which but two instruments can be connected at one time; but, on the other hand, if the plungers are pushed but part way in a simultaneous connection may be secured between more than two telephone instruments, thus changing the system from a non-interfering to an interfering one.

In some cases instead of employing the form of detent-strip illustrated in Sheet 1 of the drawings we contemplate employing a pivoted detent-strip comprising two parallel bars or strips, and we have illustrated such a construction in Figs. 5 and 6. As shown in these figures, the detent-strip 24 comprises a front strip or bar 25 for engaging the detent-piece of the plungers and a second bar or strip 26, arranged parallel therewith, for coöperating with the releasing-sections of the plungers, and in practice we have found this to be a desirable form of construction, as the distance to which the plungers must be pushed in to effect the release of the detent-strip may be made shorter than the construction before described.

We are aware that other changes may be made in the construction of our telephone-

switchboard by those who are skilled in the art without departing from the scope of our invention as expressed in the claims. We do not wish, therefore, to be limited to the forms herein shown and described; but

What we do claim, and desire to secure by Letters Patent of the United States, is—

1. As an article of manufacture, a telephone-switchboard comprising a plurality of circuit-making plungers, terminals coöperating with the plungers to form connections between telephone instruments, and a retaining device for holding the plungers in their pushed-in or operative position, whereby any desired number of plungers may be successively operated to bring a successive number of telephones into simultaneous connection, said retaining device being constructed so as to be released when one of the plungers is pushed to the limit of its travel, whereby all previously-made connections will be cut out and a connection with a single desired telephone established, substantially as described. 90

2. As an article of manufacture, a telephone-switchboard comprising a vertical face-plate, a plurality of horizontally-movable circuit-making plungers arranged in tiers over each other, springs normally forcing the plungers outwardly, contact-arms coöperating with each plunger, a vertically-movable gravity-actuated pivotally-mounted detent-strip for each tier of plungers, and a connection for simultaneously turning the detent-strips, substantially as described. 95

3. As an article of manufacture, a telephone-switchboard comprising a face-plate, a plurality of circuit-making plungers, springs normally forcing the plungers outwardly, an operating-piece rectangular in cross-section mounted on each of the plungers, contact-arms engaging opposite faces of the rectangular operating-pieces so as to hold the plungers from turning, and means for holding the plungers in their pushed-in or operative position, substantially as described. 100

4. As an article of manufacture, a telephone-switchboard comprising a face-plate, a plurality of circuit-making plungers, springs normally forcing the plungers outwardly, contact-arms coöperating with each plunger, a pivotally-mounted swinging detent-strip, a catch-section on each plunger arranged to be engaged by the detent-strip for holding the plunger in its pushed-in or operative position, and a releasing-section on each plunger separate and distinct from the catch-section thereof for raising the detent-strip to release previously-actuated push-buttons, substantially as described. 115

5. As an article of manufacture, a telephone-switchboard comprising a face-plate, a plurality of circuit-making plungers, each having an operating-section, a catch-section, and a releasing-section, springs normally forcing the plungers outwardly, a pivotally-mounted swinging detent-strip coöperating with the catch and releasing sections of the plungers, 130

and a clearing-out or releasing push-button or plunger arranged to lift the detent-strip when it is desired to release all previously-actuated circuit-making plungers, substantially as described.

6. In a telephone-switchboard, the combination of a face-plate 10, a plurality of circuit-making plungers 13, each having an operating-section, a catch-section, and a releasing-section, two sets of terminals co-operating with the operating-section of each plunger, springs 14 normally forcing the plungers outwardly, pivotally-mounted swinging detent-strips 19 for holding the plungers in their pushed-in or operative position, and a call-button for throwing in a calling-circuit when desired, substantially as described.

7. In a telephone-switchboard, the combination of a face-plate, a bridge-piece carried by said face-plate, terminals carried by said bridge-piece, and a plurality of circuit-making plungers extending through the face-plate and having their rear ends fitting into sockets which do not extend completely through the bridge-piece, substantially as described. 20 25

In testimony whereof we have hereunto set our hands in the presence of two subscribing witnesses.

OSGOOD PLUMMER.
CHAS. E. MONROE.
